UNITED STATES PATENT OFFICE.

WILLIAM SCOTT SHIELDS, OF TRENTON, NEW JERSEY.

WINDOW.

1,286,428.

Specification of Letters Patent. Patented Dec. 3, 1918.

Application filed December 31, 1917. Serial No. 209,699.

To all whom it may concern:

Be it known that I, WILLIAM SCOTT SHIELDS, a citizen of the United States, and a resident of Trenton, in the county of Mercer and State of New Jersey, have invented certain new and useful Improvements in Windows, of which the following is a specification.

My invention is an improvement in windows, and has for its object to provide mechanism in connection with the window casement and the sashes for guiding the sashes in their movement in the casing without binding or sticking and for serving as a parting strip to permit the usual parting strip to be dispensed with, and so arranged that the guide strips may contract and expand without interfering with the movement of the sashes, and wherein the sashes and the casement are grooved to receive the strips, the grooves having parallel sides and right angle corners, the strips having their sides inclined to facilitate the removal of the strips and to eliminate splitting and breaking when fitting the window or making repairs.

In the drawings:

Figure 1 is a front view of a window constructed in accordance with the improvement, and with parts in section;

Fig. 2 is a transverse section;

Fig. 3 is a vertical section;

Fig. 4 is a section on the line 4—4 of Fig. 1;

Fig. 5 is a perspective view of the guide;

Fig. 6 is a section on the line 6—6 of Fig. 7;

Fig. 7 is a section at right angles to Fig. 6.

The present embodiment of the invention is shown in connection with a casement 1 and upper and lower sashes 2 and 3, said sashes being mounted to slide vertically in the casement. Each sash has its opposite side edges vertically grooved, as indicated at 4, and the upper sash has its top grooved, as indicated at 5, while the bottom sash has its bottom grooved as indicated at 6, the grooves 4, 5 and 6 extending the full width and length of the sashes. The sides of the casement are vertically grooved, as indicated at 7, and at points where the upper sash will contact with the top of the casement, and where the lower sash will contact with the bottom of the casement, the casement is grooved, as indicated at 8 and 9, respectively, the said grooves registering with the

grooves 5 and 6 of the sashes. Within these grooves 7, 8 and 9 are arranged strips 10, 11 and 12, the said strips, as shown more particularly in Fig. 5, being trapezoidal in cross section, having their opposite faces inclined or converging toward one end of the strip. These strips are arranged within the grooves 7, 8 and 9, and are secured in place by screws 13 or the like, the said screws being arranged within longitudinally extending grooves 14 in the strips, and in that face of the strip remote from the sash.

The small edge of each strip is arranged within the groove 7, 8 or 9 as the case may be, and the large edge or base is outward and extends beyond the face of the casement to engage within the grooves 4, 5 and 6 of the sashes. Only the corners of the strips engage these grooves 4, 5 and 6, the said corners engaging the side walls of the grooves. Thus the strips serve not only as guides and parting strips for the sashes but also serve as weather strips, preventing the entrance of moisture and wind. The usual counterweights 15 are used for counterweighting the sashes, the said counterweights being connected to cords 16 which, in turn, are connected to the sashes. These cords pass over pulleys 17 which are arranged in Figs. 1 to 5 in the tops of the casement and at the tops of the sashes. In Figs. 6 and 7 the pulleys 18 over which the cords 19 pass are arranged at the sides of the sash in vertical slots in the casement 20. The construction is otherwise the same, the strips 10 being used to guide the sashes, to serve as parting strips and to serve as weather strips.

It will be noted that the depth of the groove in each strip equals the depth of the engagement of the strip in the sash groove, whereby the walls of the grooved strip are made elastic, while at the same time the tapering of the strip causes the outer corner edges only of the strip to engage in the walls of the groove in the sash.

I claim:

In a window, the combination of a casement and sashes, the casement and the sashes having registering grooves in the side edges thereof and extending the full length of the sides of the casement and sashes, and combined guide and weather strips held in the grooves in the casement and fitting within the grooves in the sashes, and serving as parting strips and weather strips, being of wood and each of the said strips having its

side walls converging toward one edge, and the said edge being received within a groove of the casement, the free edges of the strips engaging the side walls of the grooves of the sashes, each strip having a longitudinally extending groove at its large edge for receiving securing means to hold it in place and prevent expansion and contraction, the depth of the groove in the strip being equal to the depth of the engagement of the strip

in the sash groove, whereby the walls of the grooved strip are made elastic, while the tapering of the strip causes the outer corner edges only of the said strip to engage in the walls of the groove in the sash.

WILLIAM SCOTT SHIELDS.
